UNITED STATES PATENT OFFICE.

JOSEPH BERGE, OF DAYTON, OHIO, ASSIGNOR TO CHAMPION IGNITION COMPANY, OF FLINT, MICHIGAN, A CORPORATION OF MICHIGAN.

DESIGN FOR A COMBINATION CLOCK, AMMETER, AND GAUGE.

60,210.

Specification for Design.

Patented Jan. 17, 1922.

Application filed May 16, 1921. Serial No. 470,014. Term of patent 14 years.

To all whom it may concern:

Be it known that I, JOSEPH BERGE, a citizen of the United States, residing at Dayton, in the county of Montgomery and State of Ohio, have invented a new, original, and ornamental Design for a Combination Clock, Ammeter, and Gauge, of which the following is a specification, reference being had to the accompanying drawing, forming part thereof.

Figure 1 is a front elevation showing the

several separate instruments assembled in the one support or casing.

Figure 2 is a perspective view corresponding to Figure 1, the clock being removed.

I claim:

The ornamental design for a combination clock, ammeter, and gauge, as shown.

In testimony whereof I hereunto affix my signature.

JOSEPH BERGE.
